UNITED STATES PATENT OFFICE.

FRANK C. SOPER, OF CHICAGO, ILLINOIS, ASSIGNOR TO THE LUXFER
PRISM PATENTS COMPANY, OF SAME PLACE.

DESIGN FOR A VAULT-LIGHT.

SPECIFICATION forming part of Design No. 27,841, dated November 9, 1897.

Application filed September 27, 1897. Serial No. 653,261. Term of patent 14 years.

To all whom it may concern.

Be it known that I, FRANK C. SOPER, a citizen of the United States, residing at Chicago, in the county of Cook and State of Illinois, 5 have invented a certain new and original Design for Vault-Lights, of which the following is a specification.

My invention relates to a new and original design for vault-lights, and is illustrated in 10 the accompanying drawings, wherein—

Figure 1 is a front view of a vault-light embodying my invention. Fig. 2 is an end view of the same.

As illustrated in the drawings, the vault-light consists of the body portion A, provided 15 with the downwardly-projecting part or prism B. This prism may be provided at its ends

with the projecting parts B'. The prism B is provided with the converging surfaces B² B³, the forward surface B² being a convex curved 20 surface, as shown.

The essential feature of my design is a vault-light having a projecting part or prism provided with two converging surfaces, the forward or front surface being a convex 25 curved surface.

I claim—

The design for a vault-light as herein shown and described.

FRANK C. SOPER.
